(57) **CLAIM**

The ornamental design for a retaining ring for a shaft, as shown and described.

DESCRIPTION

FIG. 1 is a front view of a retaining ring for a shaft showing our new design, the rear view being a mirror image thereof; FIG. 2 is a top plan view thereof;

FIG. 3 is a bottom view thereof;

FIG. 4 is a left side view thereof, the right side view being a mirror image thereof;

FIG. 5 is an isometric view thereof; and,

FIG. 6 is a front view thereof showing the retaining ring mounted to a shaft.

The broken line showing of a shaft illustrates environment only and forms no part of the claimed design.
